L. George Hause
his ATTORNEY

UNITED STATES PATENT OFFICE

SAMUEL MARCUS, OF RIVERDALE, NEW YORK, ASSIGNOR TO MARKON MANUFACTURING CO., INC., OF NEW YORK, N. Y., A CORPORATION OF NEW YORK

DOLL HEAD

Application filed August 28, 1928. Serial No. 302,548.

This invention relates to an improvement in doll heads.

An object of the invention is to provide means therein adapted for the attachment of eye sets and particularly adapted for definitely locating the eye sets with respect to the usual eye openings of the head.

A further object is to provide simple, efficient and practical means for assisting in quickly and conveniently and precisely locating the eye sets, and being of a character such that parts of the eye set may be readily impaled thereinto for retaining the eye set against dislodgment.

A more detailed object is to provide a doll head having the usual eye openings in its frontal wall and having parts to which an eye set may be attached, and said doll head also having suitable shoulder or abutment parts provided therein upon opposite walls of the head, either horizontally or vertically, adapted to receive widely spaced portions of the eye set for thereby definitely positioning the eye set preparatory to fastening the eye set within the head.

A further object is to provide wall parts within the head associated with said shoulders or abutments respectively and co-operative therewith to receive and retain the eye set.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claim.

In the accompanying drawings which are to be taken as a part of this specification, and in which I have shown merely a preferred form of embodiment of the invention:—

Fig. 1 is a vertical sectional view through a portion of a doll head showing the same as being provided with shoulder or abutment parts therein in accordance with this invention.

Fig. 2 is a transverse sectional view taken upon the plane of line II—II of Fig. 1.

Fig. 3 is a vertical sectional view through the front wall of a doll head showing a modified arrangement of the shoulders or abutments, these parts being here shown arranged one above the other for accommodating a vertical eye set carrier whereas in the structure Figs. 1 and 2 said parts are arranged horizontally opposite to each other for accommodating a horizontal eye set carrier, and

Fig. 4 is a fragmentary detail view illustrating the use of a separate insert moulded or otherwise attached in the doll head providing shoulder or abutment parts in accordance with this invention.

In the patent to Konoff 1,621,072 issued March 15th, 1927, there is illustrated a doll head having portions of its frontal wall, in the region between the two eye openings, arranged as abutments to be engaged by parts of the eye set carrier for limiting forward movement of the carrier toward said eye openings, thereby to determine the position of the carrier preparatory to the final act of attaching the carrier rigidly within the head. The eye set carrier shown in said patent includes attaching parts which are spaced away from the mentioned abutment engaging parts.

By the present invention it is contemplated that the abutment engaging parts of the eye set carrier shall be brought into closer proximity to the attaching parts of said carrier, and it is proposed accordingly that the head, which is generally indicated in the drawing by the reference character L, shall be provided with shoulders or abutments as G and H upon the opposite walls thereof, both facing rearwardly and being in a vertical plane which is predetermined with respect to the vertical plane of the eye openings 1 and 2 of the head.

These abutments are also preferably arranged adjacent to wall surface parts as 3 and 4 respectively of the head, said wall surface parts being in opposition to each other across the head and being adapted to be engaged by the attaching members of the eye set carrier for holding said carrier in operative position as clearly indicated.

The abutments stand in a common substan-

tially vertical plane and have a suitable surface extent so that said carrier may be adjustably moved to any selected position in said vertical plane as may be desired for properly positioning the eyes, as 5 and 6 of the eye set within the head openings 1 and 2 preparatory to fastening the carrier within the head.

Both the wall parts 3 and 4, and the abutments G and H, may be, and preferably are, of a character to permit the eye set carrier to be attached in position by being impaled in said wall parts or abutments if desired, and to this end the modification Fig. 4 suggests that if preferred said wall parts and abutments may be provided upon members as 7, Fig. 4, moulded or otherwise attached in position within the doll head, said members being in this case formed of material, such as wood or the like, which is particularly well adapted for the impaling of the attaching parts of the eye set thereinto.

It will be understood of course that the separately formed inserts 7 will be preferably duplicated at opposite walls of the head.

Where the doll head is made of moulded wood pulp or other similar composition it is sometimes sufficient however to make the abutments and wall parts both as integral portions of the material of the head.

Also, in instances where the eye set is to be attached by other means than by being impaled into the head, the abutments and wall parts may be moulded as integral features of the interior wall surface of the head.

Given a doll head having the spaced abutments as G and H therein with their adjacent wall parts 3 and 4, and an eye set of the general type indicated, the operator has merely to introduce the eye set into the head with the two eye portions 5 and 6 within the eye openings 1 and 2 and with the opposite ends of the carrier part 8 of the eye set resting upon the abutments, and then fastening the carrier portion in position as by driving out the attaching members 9 and 10 of the set against or into the walls 3 and 4.

The abutments G and H may directly receive the attaching members 9 and 10, as indicated in Figs. 1 and 2, for limiting forward movement of the set toward the frontal wall of the head, or they may directly receive the main body part of the carrier as in Fig. 3, according to preference and design.

When either the attaching members, or the carrier, as the case may be, is brought to rest upon the abutments the movement of the carrier toward the frontal wall ceases, and it is of course intended that the relationship between the vertical plane of the abutments and the vertical plane of the eye openings is such that at this moment the eye balls will have moved forward into the eye openings just the desired distance. The carrier may

now be shifted to a suitable extent in a vertical plane, that is with the carrier, or the attaching members, resting upon the abutments, until the eye balls are centered with the desired accuracy within the eye openings. This having been done the operation of driving the attaching members home for fixing the carrier against further movement is performed thus completing the operation.

Both the material of the abutments G and H and the material comprising the walls 3 and 4 may be of a character such that tangs or other fastening or locating devices provided upon the eye set may be impaled thereinto if desired.

The abutments may receive impaled thereinto for example one or more forwardly projecting tangs or prick-points as 11, provided upon the eye set for guarding against any lateral movement of the eye set during the time while the attaching devices are being driven home.

The walls 3 and 4 may have impaled thereinto for example one or more tangs or prick-points as 12 provided upon the eye set as parts of the attaching devices.

It will be seen from the foregoing that a head constructed in accordance with this invention presents no moulding difficulties. The abutments and the opposing wall parts may readily be provided during the moulding operation and without in any way complicating said operation. Once the dies are prepared from which to mould the head any number of heads may be produced from said moulds all bearing exactly the same relationship as between the eye openings and the abutments and the opposing wall parts so that machine made eye sets may be quickly and easily attached within said head with great efficiency and substantially uniform accuracy.

The fact that the abutments are widely spaced from each other across the region of the eye openings so as to be engaged by correspondingly spaced portions of the eye set avoids the necessity for extreme accuracy since any slight variation in the details of the manufactured product will be considerably minimized in their effect upon the fit of the eye balls within the eye openings.

That is to say for instance that the effect of a slight misplacement of one of the abutments, due to shrinkage or other causes, will be reduced by approximately 50 per cent in its effect upon the position of the eye balls, this because of the location of the eye balls at a point substantially midway between the two abutments.

Moreover both end portions of the eye set carrier will be positively supported in a definite location, and the mid-portion of the carrier, to which the eye balls are connected will of course be definitely located in consequence.

As many changes could be made in this

construction without departing from the scope of the invention as defined in the following claim, it is intended that all matter contained in the above description, or shown in the accompanying drawings, shall be interpreted as illustrative only and not in a limiting sense.

Having thus described my invention, what I claim as new and desire to secure by Letters Patent is:—

As an article of manufacture, a doll head having the usual eye sockets in its front wall and having other walls extending rearwardly from said front wall, one of said mentioned other walls being constructed interiorly of the head to provide a rearwardly facing abutment thereon, and an opposite one of said mentioned other walls being constructed interiorly of the head to provide a second rearwardly facing abutment thereon so that said two abutments are spaced apart at opposite sides of the region of the eye openings in predetermined relation to said eye openings and facing in a common direction away from said openings to serve as stops for receiving an eye set thereagainst in operative relation to said eye openings, said mentioned other walls being also constructed to provide wall surfaces adjacent said abutments respectively to be engaged by attaching means of the eye set for there fixing the eye set with respect to said abutments, each abutment being in right angular relation to its respective adjacent wall surface, the abutments consisting of flat surfaces facing rearwardly of the head and the wall surfaces being flat and facing toward each other and extending rearwardly from the respective abutments, and the material providing all said wall surfaces and abutments being of a character rendering it readily penetrable by prongs of the eye set driven thereinto.

In testimony whereof I affix my signature.

SAMUEL MARCUS.
